(57) **CLAIM**

The ornamental design for a hockey puck bottle stopper, as shown and described.

DESCRIPTION

FIG. 1 is a front perspective view of a hockey puck bottle stopper showing the new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof;

FIG. 7 is a bottom plan view thereof; and,

FIG. 8 is a front perspective view of the hockey puck bottle stopper of FIG. 1 shown in a position of use with a logo and a bottle, both of which are drawn in broken lines.

The broken line and unshaded areas in FIG. 7 depict portions of the hockey puck bottle stopper that form no part of the claimed design. The broken lines in FIG. 8 illustrating a logo and a bottle depict environment and form no part of the claimed design.

1 Claim, 8 Drawing Sheets
